UNITED STATES PATENT OFFICE.

RICHARD PFAEHLER, OF CHARLOTTE, NORTH CAROLINA, AND INGENUIN HECHENBLEIKNER, OF GREAT FALLS, SOUTH CAROLINA, ASSIGNEES TO SOUTHERN ELECTRO-CHEMICAL COMPANY, OF CHARLOTTE, NORTH CAROLINA, A CORPORATION OF NEW JERSEY.

ELECTRIC FURNACE FOR PRODUCING ENDOOTHERMIC GAS REACTIONS.

1,249,479.

Specification of Letters Patent.

Patented Dec. 11, 1917.

Application filed August 26, 1913. Serial No. 786,767.

To all whom it may concern:

Be it known that we, RICHARD PFAEHLER and INGENUIN HECHENBLEIKNER, subjects of the Emperor of Germany and Emperor of Austria, respectively, residing at Charlotte, in the county of Mecklenburg and State of North Carolina, and Great Falls, county of Chester, South Carolina, respectively, have invented new and useful Improvements in Electric Furnaces for Producing Endothermic Gas Reactions, of which the following is a specification.

The present invention relates to an improved method of an electric furnace for, producing endothermic gas reactions in the production of nitrogen oxids from the air, and has for its objects to greatly simplify and improve methods and furnaces of this type and render the same more certain, reliable and efficient in operation.

In the process for producing endothermic gas reactions, as for instance the formation of nitrogen oxids from the air by means of the electric arc, the amount of formed nitric oxids increases with the rise of temperature.

These reactions belong, however, to the class of reversible reactions. Unless the highly heated gases are rapidly cooled down, a decomposition or dissociation of the formed nitric oxide gases takes place.

In the methods thus far in use, it is sought to effect the cooling or chilling by mixing the hot reaction gases with the cold part of the air first introduced or with separately introduced cold air, or by subjecting the hot reaction gases to cooled metal surfaces or rotating metal disks.

The various types of apparatus devised to attain this object are, however, not very efficient and are more or less the cause of serious troubles in connection with the operation of the electric furnace.

In the furnace herein described and which forms the subject matter of the present invention, new methods and means are em-

ployed to cool down the hot gases so rapidly that the formed nitric oxide has practically no time to undergo decomposition and in addition the length of the electric arc is materially increased.

Referring to Letters Patent No. 887,220, dated May 12, 1908, and No. 1,029,886, dated June 18, 1912, relating to a pair of auxiliary electrodes that are electrically connected to a pair of diverging electrodes for starting the electric arc, the tips of the auxiliary electrodes or commonly called "kindling blades" are cooled by the current of air blown through the space between the main electrodes.

It has been found that this current of air must be forced through the above mentioned space under a comparatively high pressure so as to prevent the kindling blades from being too quickly burned up. In the methods now in use, all the air to be treated in the electric arc, is blown into the reaction chamber through one nozzle. This arrangement consequently requires a considerable amount of auxiliary power for driving the blower furnishing this air current of high pressure.

One object of the present invention is to reduce the power needed for driving the auxiliary machinery by introducing the strong air current which is especially required for the cooling of the tips of the kindling blades, through a separate nozzle.

Referring to Letters Patent No. 1,029,885, dated June 18, 1912, describing a water cooled electrode constructed of three parts, experience has shown that the upper part is the cause of frequent electric short circuits and that it is rather difficult to satisfactorily insulate this upper part from the furnace walls so as to prevent burning out of the insulation and adjacent parts.

Another object of the invention is to prevent these troubles by entirely omitting this upper part of the electrode and providing an improved construction of cooled elec-

trode, the diverging member of which terminates wholly within the reaction chamber of the furnaces.

By this means the cooling surface of the electrode proper is also considerably reduced and the heat, which was formerly absorbed by the cooling water passing through this upper part, can be utilized in the process.

An embodiment of all of the above named 10 improvements together with others which will be made clear in the detailed description to follow, is shown in the accompanying drawing forming part of this specification, wherein—

15 Figure 1 is a top plan view of the furnace, including the gas cooler and auxiliary machinery.

Fig. 2 is a vertical section along the line A—B—C—D, Fig. 1.

20 Fig. 3 is another vertical section along the line E—F, Fig. 2.

Fig. 4 is a front elevation of the electrode stand.

25 Fig. 5 is a vertical section on an enlarged scale, through the lower portion of the furnace chamber, one of the electrodes being shown in elevation.

30 Figs. 6, 7, and 8 are cross-sections through the electrode and electrode tubes, respectively, and

35 Fig. 9 is a top plan view of the low pressure air nozzle.

These last named three sections and one view are drawn at a still more enlarged scale.

35 Like letters of reference denote corresponding parts in all the views and sections, respectively.

40 As shown in the drawings, the furnace chamber consists of an iron casing 1, which is built up on the base plate 2. The base plate 2 rests on the beams 3 and 4, which are supported by the brackets 5, 6, 7 and 8. These four brackets are securely fastened to the four vertical columns 9, 10, 11 and 12.

45 The casing 1 is lined with firebrick or some suitable refractory material 13, two opposite walls of which are inclined or flare outwardly and upwardly from the base as more clearly shown in Fig. 2.

50 The extension of the casing 1 consists of the reducer 14 slightly contracted at its upper end, and of the flue 15, which is connected with the gas cooler 16. The reducer 14 and the flue 15 are also lined with refractory material 17, which forms an extension of the line 13, the parts 1 and 14, with their linings 13, and 17 forming a furnace chamber of novel construction.

55 The horn shaped stationary electrodes which are also of novel shape and construction, are shown in detail in Figs. 5 to 8, inclusive. In Fig. 5 one electrode is shown in section and the other electrode in elevation.

Both electrodes are duplicates and similar parts are marked by the same numeral.

65 The electrode proper consists of the main part 18 and the lower part 19, both of which parts are made of cast iron. The lower part 19 is provided with a pipe tap suitable for the insertion of the tube 20. The tube 21 of smaller diameter is located inside of the tube 20. The annular space between the tubes 20 and 21 is divided in two spaces 28 and 29 by the partitions 22 and 23, which extend throughout the entire length of the 70 tube 20. Both ends of the tube 20 are closed by the rings 24 and 25. Near the end of tube 20 outside of the furnace chamber, the pipe-nozzles 26 and 27 are welded on the tube 20. The nozzle 26 Fig. 8, connects with 75 the space 28 and the nozzle 27 with the space 29.

80 The nozzle 26 is suitably connected with some cooling water supply. This water passes then through the space 28 and flows through the opening 30 in the tube 20 into the corresponding canal 31 provided in the lower part 19. The main part 18 is clamped to the lower part 19 by the bolts 34 and the canal 32 is an extension of canal 31. The water thus flows through the canal 32 in the part 18, of the electrode and returns through the canal 33.

85 Another canal opposite and similar to canal 31 formed in the lower part 19 of the electrode, conveys the water through an opening opposite the opening 30 into the space 29 and the water then finally discharges through the nozzle 27.

90 The adjustable auxiliary electrodes or "kindling blades" 35 are located inside of the tube 21 and pass through a slot formed in the lower part 19 between the two canals 31. The outer end of the kindling blade 35 is attached to the rack 36 with which a pinion 105 36', engages, by means of which the electrodes may be adjusted toward and from each other.

95 Referring again to the main part 18, it will be noticed in Figs. 5 and 7 that the portion or wall of the electrode that is exposed to the action of the flame is of increased thickness and the life of the electrode is thereby lengthened, that is to say, the electrodes do not burn out so quickly.

100 The electrode tubes 20 are insulated from the metal doors 37 by the insulating bushing 78 as more clearly shown in Figs. 2 and 5.

105 Experience has shown that the shape of the reaction chamber should conform to the shape of the electrodes so as to prevent eddies and other air disturbances, which tend to deflect the arc, and cause short circuits. The reaction chamber 38 is built upon these 115 principles. The opening left for the inser-

tion of the electrode will be closed by the door brick 39, which is securely fastened to the iron door 40. In order to be able to quickly replace and remove this door-brick 39, the trolley carriage 42 traveling along the runway 43 is employed. At the upper end, the iron door 40 is provided with two projections, in which the holes 44 and 45 are drilled, and at the lower end with a third projection 46.

The trolley carriage 42 is provided with the angle levers 47 and 48. By bringing the carriage 42 toward the iron door 40, the holes 49 and 50 drilled in the levers 47 and 15 48 will come opposite the holes 44 and 45 and a suitable pin will be placed through all of these holes, thus connecting the door 40 to which the firebrick 39 is attached, with the trolley carriage 42.

20 When the furnace is in operation the iron door 40 is suitably bolted or clamped to the iron casing 1.

With the trolley carriage 42 connected to the door 40 by the above described method, 25 the attachments on the door 40 can be removed and due to its own weight the door 40 with its projection 46 will rest against the stop 51 provided at the bottom of the carriage 42.

30 For the purpose of making small adjustments the trolley carriage 42 is provided with the turnbuckle arrangement 52.

The placing or removing of the electrode is done by using the electrode carriage 53 35 as more clearly shown in Fig. 2. The electrode stand 54 is provided with three projections similar to those used on the iron door 40. The removed electrode attached to the electrode carriage 53 is shown in dotted lines 40 in Fig. 2.

45 As previously mentioned, the air or gas mixture to be treated in the electric arc according to the present invention is blown into the reaction chamber through two nozzles.

The current of air which is especially required for the cooling of the kindling blades 35 is furnished by the high pressure blower 55 and delivered into the reaction chamber 38 through the pipe line 56 and nozzle 57, 50 respectively, as more clearly shown in Figs. 3 and 5.

The low pressure air is furnished by the blower 58, Figs. 2, 3, and 5. This air is then passed through the pipe line 59 and discharged through the nozzle 60 into the space between the main electrodes. As will be seen by referring to Figs. 5 and 9, the low pressure nozzle 60 is provided with two side outlets 61 and 62 that are directed outwardly 55 or laterally for the purpose of furnishing cooling air to the insulating bushings 78 to prevent these and their adjacent parts from burning out.

The hot gases after having been treated in the electric arc formed between the electrodes 18, pass through the flue 15 into the gas cooler 16 where they are cooled down to some desired temperature below 2000 degrees C. The comparatively cool gases leave the gas cooler 16 through the pipe line 63. This 60 pipe line 63 is tapped by the pipe-line 64, which is connected to the exhauster 65. The outlet of the fan 65 is connected with the pipe line 66, which branches off to the conduits 67 and 68 attached to the base plate 2. 70 The extension of these conduits 67 and 68 through the base plate 2 and through the furnace lining 17 is formed by the ducts 69 and 70, traversing the lower portion of the furnace chamber as more clearly seen in 75 Fig. 3.

These ducts 69 and 70 connect with the reaction chamber 38 through the elongated slots 71 and 72, which extend over the entire distance between the electrode parts 18 just 80 above the zone of maximum heating of the electric arc.

The low pressure air pipe-line 59 is connected with the conduits 67 and 68 by the branches 73 and 74. The gates or valves 75 90 and 76 are built in the branch pipes 73 and 74 and as shown in Fig. 3, both are closed but may be adjusted to regulate the volume of air introduced into the furnace chamber.

Now, part of the gases leaving the gas 95 cooler 16 through the pipe line 63 are drawn off by the exhauster 65 through the pipe line 64. The valve 77 placed in the pipe line 64 may be used for regulating the volume of gases to be returned.

100 By the action of the fan 65 the return gases are then forced through the pipe line 66, through the conduits 67 and 68 and through the ducts 69 and 70 and finally blown into the reaction chamber 38 through the slots 71 and 72 just above the zone of maximum heating of the electric arc.

105 The result of this arrangement is that the comparatively cold return gases suddenly cool-off the highly heated reaction gases to a 110 temperature which is below the critical temperature, so that a decomposition of the nitric oxide gases formed in the electric arc is reduced to a minimum.

On the other hand, the gases returned into 115 the chamber 38 through the slots 71 and 72, practically contain the same percentage of nitric oxide gases, by volume, as the gases treated in the electric arc, and the treated gases will not, therefore, be diluted by this 120 method.

If, for some other reason, it is desired to mix the return gases with a part of the low pressure air or gas mixture passing through the pipe line 59, the gates or valves 75 and 76 125 may be suitably opened.

The return gas supply through the pipe line 64 may be also entirely cut off by closing the valve 77.

As illustrated, especially in Fig. 3, the direction of the cool gases or gas mixtures forced through the slots 71 and 72 into the reaction chamber 38, is such as to produce the effects of an injector. The length of the electric arc formed between the electrode pair 18, will by this arrangement be considerably increased, thus improving the electrical conditions of the furnace.

What we claim is:

1. An electric furnace of the character described having a reaction chamber, opposite walls of which diverge from the base of the furnace upwardly, each of said diverging walls having an opening therethrough and a movable closure therefor, and a pair of opposed electrodes arranged in said chamber, one opposite each closure, and each electrode having a diverging part conforming substantially to the contour of a diverging wall of the chamber of the furnace and adapted to be withdrawn therefrom through the opening in its diverging wall.

2. An electric furnace of the character described having a reaction chamber, a pair of oppositely disposed hollow electrodes arranged within said chamber, each electrode having a diverging part terminating wholly within the chamber, and a return passage in said part, and means for circulating a cooling medium through the return passage in the diverging part of said electrodes.

3. In an electric furnace of the character described having a reaction chamber, a pair of opposed electrodes arranged within said chamber, a pair of kindling-blades associated with said electrodes, and separate nozzles for delivering air into the furnace chamber, one of said nozzles being arranged to deliver a current of cooling air against the said kindling-blades.

4. In an electric furnace of the character described having a reaction chamber, a pair of opposed electrodes arranged within said chamber, a pair of kindling blades associated with said electrodes, separate nozzles for delivering air into the furnace chamber, one of said nozzles being arranged to deliver a current of high pressure air against the said kindling blades for cooling the latter.

5. In an electric furnace of the character described having a reaction chamber, a pair of opposed electrodes arranged within said chamber, a pair of kindling blades associated with said electrodes, separate nozzles for delivering air into the furnace chamber, one of said nozzles being arranged to deliver a current of high pressure air against

the said kindling blades for cooling the latter, and separate sources of supply for the said nozzles.

6. In an electric furnace of the character described having a reaction chamber, a pair of opposed electrodes arranged within said chamber, each electrode having a portion extending through and insulated from the furnace wall, a nozzle for delivering air into the furnace chamber, and means for directing a current of cooling air against the insulated portion of each electrode. 75

7. In an electric furnace of the character described having a reaction chamber, a pair of opposed electrodes arranged within said chamber, each electrode having a portion extending through and insulated from the furnace wall, a nozzle for delivering air into the furnace chamber, and means forming a part of said nozzle for directing a current of cooling air against the insulated portion of each electrode. 85

8. In an electric furnace of the character described having a reaction chamber, a pair of opposed electrodes arranged within said chamber, each electrode having a portion extending through and insulated from the furnace wall, a nozzle for delivering air into the furnace chamber, and separate laterally directed outlet ports associated with said nozzle for delivering a current of cooling air against the insulated portion of each electrode. 95

9. In an electric furnace of the character described having a reaction chamber, a pair of opposed electrodes arranged within said chamber, doors in the opposite walls of the chamber through which said electrodes may be inserted and removed, a door-supporting carriage movable toward and from each of the said doors, and means for detachably connecting each door to its associated carriage. 100

10. In an electric furnace of the character described having a reaction chamber, a pair of opposed electrodes arranged within said chamber, doors in the opposite walls of the chamber through which said electrodes may be inserted and removed, a door-supporting carriage movable toward and from each of the said doors, a trolley for each carriage, and means for detachably connecting each door to its associated carriage. 110

11. In an electric furnace of the character described having a reaction chamber, a pair of opposed electrodes arranged within said chamber, doors in the opposed walls of the furnace through which said electrodes may be inserted and removed, a bracket outside the furnace for supporting each electrode, and a carriage provided with means for attachment to the brackets of the electrodes 120 for withdrawing and replacing the same. 125

12. An electric furnace of the character described having a reaction chamber, and a pair of opposed electrodes arranged within said chamber, each electrode having a diverging member terminating wholly within the chamber and each electrode member provided with a return passage through which a cooling medium may be circulated.

13. An electric furnace of the character described having a reaction chamber, a pair of opposed electrodes arranged therein, each electrode comprising a base member 19 and a diverging member 18, removably attached to the said base member and terminating

wholly within the said chamber, and means 15 for circulating a cooling medium through the two members of each electrode.

In testimony whereof we have hereunto set our hands in presence of subscribing witnesses.
